UNITED STATES PATENT OFFICE.

JACOB F. HESS, FREDRICK H. SNYDER, LENERD HESS, JACOB F. SNYDER,
AND CHARLES F. SNYDER, OF MASSILLON, OHIO.

STOVE.

SPECIFICATION forming part of Letters Patent No. 356,686, dated January 25, 1887.

Application filed June 28, 1886. Serial No. 206,410. (No model.)

To all whom it may concern:

Be it known that we, JACOB F. HESS, FREDRICK H. SNYDER, LENERD HESS, JACOB F. SNYDER, and CHARLES F. SNYDER, of Massillon, in the county of Stark and State of Ohio, have invented certain new and useful Improvements in Stoves; and we do hereby declare that the following is a full, clear, and exact description of the invention, which will enable others skilled in the art to which it appertains to make and use the same, reference being had to the accompanying drawings, which form a part of this specification, and in which—

15 Figure 1 is a perspective view of our improved heating-stove, showing portions broken away. Fig. 2 is a vertical sectional view taken through the front side of the stove. Fig. 3 is a similar view taken on line $\alpha\alpha$, Fig. 2; and 20 Fig. 4 is a perspective view of the expandible magazine.

Similar letters of reference indicate corresponding parts in all the figures.

Our invention has relation to that class of 25 stoves for heating purposes usually called "base-burning" or "magazine" stoves; and it consists in the improved construction and combination of parts of such a stove, which is provided with an expandible magazine and 30 with a chute for filling the coal into the magazine, provided with a sliding damper, by means of which the feed-aperture in the top of the magazine may be closed, as hereinafter more fully described and claimed.

35 In the accompanying drawings, the letter A indicates the body of the stove, which body is rectangularly prismatic and provided with suitable doors, B, in the sides, and the base of this body, which base is lettered C, is provided with the fire-pot or furnace D and with the ash-pit E, while the upper end of the body is covered with the top F.

The upper end of the body of the stove is provided with small brackets G in the corners, 45 and the lugs H, projecting from the corners of the top plate of the magazine I, rest upon these brackets supporting the magazine.

The magazine consists of the top plate, J, which is provided with the feed-aperture K so at its middle, through which the coals are fed, and the side pieces, L, and the corner pieces,

M, and the sides of the feed-aperture are provided with parallel flanges N N, which rise toward the forward side of the stove, forming a chute, O, opening through the top of the 55 stove.

A damper, P, slides upon the top plate of the magazine and between the flanges, and the forward edge of this damper is provided with an upwardly-projecting deflecting-flange, Q, 60 while the rear edge of the damper is provided with a handle, R, sliding through the side of the stove, the deflecting-flange serving to prevent the coals, when fed into the chute, from falling upon the upper side of the sliding 65 damper, which is drawn back, deflecting the coals into the aperture.

The top of the stove is provided with the stove-pipe S, which is secured in it, the smoke passing from the fire-pot or furnace along the 70 sides of the magazine to the top of the stove, where it is carried away through the stove-pipe.

The side pieces of the magazine increase slightly in width toward their lower ends, 75 having inclined side edges, and the upper edges of the side pieces are provided with upwardly-projecting perforated flat ears T, in planes at right angles to the planes of the side pieces, and these perforated ears pass up 80 through slots U in the top piece of the magazine, and have rods V passed through them, allowing the side plates to be thus hinged to the top piece or plate.

The corner-pieces of the magazine consist 85 of plates bent at right angles and having slightly inclined side edges, increasing in width toward the lower ends, and the upper ends of these corner-pieces are formed with lips W, having perforations and passing 90 through diagonal slots X in the corners of the top plate, pins Y, passing through the perforated lips or ears, hinging the corner-pieces upon the top plate.

The side plates are provided with strips or 95 fingers Z, secured upon the outer sides near the lower ends of the side edges and parallel with the lower edges, the said strips or fingers being secured at their inner ends and projecting over the lower portions of the corner-pieces, 100 and the lower ends of the flanges of the corner-pieces are provided with outwardly-pro-

jecting lips A', which will bear against the inner sides of the stove and prevent the side plates of the magazine from being spread so far apart that they would obstruct the smoke-passages between the sides of the stove and the sides of the magazine.

It will be seen that the magazine will be expanded when coals are filled into it, the weight of the coals forcing the sides apart, and as the 10 supply in the magazine decreases the side plates will fall back and by contracting expose a smaller body of coal to the fire in the fire-pot, while when the supply is larger a larger body of coal is exposed to the action of 15 the fire, thus equalizing the combustion in the fire-pot by exposing a larger body of coals to the action of the fire when the magazine is expanded and consequently the draft is less, and exposing a smaller body of coal to the action 20 of the fire when the magazine is contracted and the draft greater, the fire-surface, however, being smaller when the larger body of coal is exposed to the action of the fire, and larger when the smaller body of coal is exposed, thus causing the draft to be in inverted 25 proportion to the body of coal exposed to the fire and in direct proportion to the amount of fire-surface exposed.

Having thus described our invention, we 30 claim and desire to secure by Letters Patent of the United States—

1. The combination of a heating-stove and a magazine, the lower end of which is below the smoke-pipe and expansible, as and for the 35 purpose shown and set forth.

2. In a base-burning heating-stove, the combination of a body having brackets in the upper corners, a top plate for the magazine having a feed-aperture and having lugs at its 40 corners resting upon the brackets, side plates hinged at their upper edges to the top plate and having diverging side edges, and rectangularly-bent corner-pieces hinged to the top plate and fitting with the side flanges over the 45 side edges of the side plates, as and for the purpose shown and set forth.

3. In a base-burning heating-stove, the combination of a body having brackets in the upper corners, a magazine top plate having lugs projecting from its corners and resting in the 50 brackets, and having a feed-aperture covered with a sliding damper and formed with slots in its corners and near its side edges, side plates having diverging side edges, and having perforated ears at the upper ends secured through the slots in the top plate by means of 55 rods, and having outwardly-pointing fingers or strips near the lower edges, and rectangularly-bent corner-pieces having perforated ears at the upper ends pivoted upon pins in the slots 60 at the corners of the top plate, and having their flanges sliding under the fingers of the side plates, and having outwardly-projecting lips near the lower ends of the side flanges, as and for the purpose shown and set forth.

4. In a base-burning heating-stove, the combination of a stove-body having a feed-aperture in the front side of the top, a magazine supported in the stove-body and having a feed-aperture in its top, parallel flanges at the sides 70 of the feed-aperture and extended to form a chute-opening through the feed-aperture in the top of the stove, and a damper sliding between the flanges, and having a handle passing out through the back of the stove, and having an 75 upwardly-projecting deflecting-flange at its forward edge, as and for the purpose shown and set forth.

In testimony that we claim the foregoing as our own we have hereunto affixed our signatures in presence of two witnesses.
